HENRY J. KASCH, OF DAYTON, OHIO, ASSIGNOR TO THE KURZ-KASCH COMPANY, OF SOUTH BROADWAY, NEAR DAYTON, OHIO, A CORPORATION OF OHIO.

VERNIER DIAL.

Application filed January 26, 1925. Serial No. 4,789.

This invention relates to new and useful improvements in vernier dials.

It is the principal object of my invention to provide a vernier dial which is particularly adapted for radio use so that an extremely minute and accurate adjustment of a condenser or other part may be obtained. With my vernier dial it is easy to obtain, with accuracy, stations whose dial logs or readings terminate in fractions such as tenths.

My vernier dial is simple in construction, it is economical to make and has an easy and silent operation.

In the accompanying drawings, Figure 1 is a front view of my improved vernier dial. Figure 2 is a sectional view thereof taken on the line 2-2 of Figure 1. Figure 3 is a sectional view taken through the same on the line 3-3 of Figure 1. And Figure 4 is a plan view of the dial, showing the vernier attachment in its relation thereto.

Referring to the accompanying drawings, the numeral 1 designates a dial such as is used in radio apparatus, and formed with a beveled edge containing preferably upon one half of its circumference equally spaced graduations from 0 to 100, although any greater or less number may be provided on it if desired. This dial, which is preferably constructed of bakelite, has an outwardly projecting hub portion 2 to receive the outer end of a shaft such as the condenser shaft 3 which projects through a hole in a panel 4. To the latter there is secured, by screws 5, 5, a vernier plate 6 in a suitable position to bring its graduations, which are represented by 11 equally spaced lines extending radially to the inner curved edge of it, for co-incidence with the divisions on the dial scale when the latter is turned the proper distance by the means now to be described.

The dial is formed substantially between its center and its outer graduated portion, with a semi-circular slot 7 which permits the dial to be moved the length of the slot over the head of a screw 8 and the downwardly and forwardly turned end 9 of an arm 10 which said screw fixedly secures to the panel 4. The arm 10 is preferably formed in the shape of a paddle, with its widened portion slightly inclined to that of its handle part and provided with a central hole through which the hub 2 of the dial freely projects.

Pivots secured by a pin 11 to one outer

corner of the enlarged part of the arm 10, below the latter, is a gear 12 which is preferably constructed of bakelite. This gear meshes with teeth 13 preferably formed of bakelite around an inner, annular shoulder 14 provided on the dial 1.

Pivots secured within the other outer corner part of the enlarged portion of the arm 10, is the stem of a pinion 15 which lies below the arm for mesh with the gear 12. The stem of the pinion 15 terminates above the arm in a reduced portion 16 to which there is fixedly secured a gear 17 preferably constructed of bakelite. This gear meshes with the teeth 18 formed on the exterior part of the inner end of the inner tubular extension or sleeve 19 of a knob 20. This knob, which is preferably made of bakelite, is frusto-conical, being at its inner end formed with a rim which tapers outwardly from its normally inclined part, and then downwardly in line with its axis to bridge the annular toothed portion 13 of the dial.

The knob 20 is free to turn loosely around the dial hub 2 which is formed to receive a split sleeve 21 that is tapered at its inner end and externally threaded at its outer end to receive a lock nut 22. Adapted to be screwed upon the threaded end of the tapered sleeve 21 beyond the lock nut 22, is the interiorly threaded hub 23 of a small outer knob 24. The hub portion 23 of the latter near its inner end is formed with a shoulder 25 that seats against the top of the large knob 20 which is free to be turned independently of the latter.

When my vernier dial unit is assembled, the split tapered sleeve 21 within the hub 2 of the dial, is slipped on the shaft 3 against the panel 4. The lock nut 22 is then screwed on the sleeve a sufficient distance to cause the tapered wall of the dial hub to press the tapered part of the sleeve tightly against the shaft 3 to establish a non-slipping connection with it. The small knob 24 is then screwed on the sleeve above the lock nut.

In operation, when it is desired to turn the dial 1 to bring one of its division lines into co-incidence with a graduation line on the vernier plate 6, the knob 20 is rotated by the fingers. When the knob 20 is turned, its inner toothed periphery 18, which is in mesh with the gear 17, will rotate the latter. This gear 17 being secured to the pinion stem 16, will turn the pinion 15 which is in

mesh with the gear 12. Since the latter gear is in engagement with the teeth 13 formed on the dial 1, it will turn the latter, when the knob 20 is rotated, in a ratio of 5 10 to 1.

If a broadcasting station whose dial log is 64.8 is desired, the knob 20 is turned counterclockwise until the division line 64 on the dial co-incides with the 0 graduation 10 on the vernier plate 6. The rotation of the knob 20 is then continued until the first division line on the dial next behind the graduation line 8 on the vernier plate 6, is brought into alignment with said graduation 15 line. (See Figure 4.) It is thus possible, readily and accurately, to turn the dial 1, and through it the condenser shaft 3, the distance necessary to obtain a station whose dial log or reading is represented by a whole 20 number and a fraction.

Having described my invention, I claim:

1. In a device of the type described, a panel containing a hole, a shaft projecting through said hole, a dial secured to said 25 shaft and formed with a curved slot, a knob free to turn around said shaft, an arm between the knob and dial, means projecting loosely through the curved slot in the dial for securing one end of the arm to said panel, 30 said dial having an offset toothed annular portion and the knob an outer toothed periphery, and a gear-train secured to the free end of said arm for operative connection between the toothed portions of the knob and dial, to turn the latter and through it the 35 shaft when the knob is rotated.

2. In a device of the type described, a panel containing a hole, a shaft projecting through said hole, a dial secured to said 40 shaft and formed with a curved slot, said dial also having an outwardly extending hub portion, a knob having an interior tubular extension formed with an annular row of external teeth, rotatable around the hub por-

tion of the dial; said dial formed with a 45 curved slot, an arm between the knob and dial, means projecting loosely through the curved slot in the dial for securing one end of said arm to the panel, said dial having an outer, offset toothed annular portion, a 50 pinion, a stem for the latter pivotally secured in the free end of said arm, a gear on said stem in mesh with the toothed tubular extension of said knob, and a gear pivotally secured to said arm, in mesh with the 55 pinion and the annular toothed portion of the dial to turn the latter; and through it the shaft, when the knob is rotated.

3. In a device of the type described, a panel containing a hole, a shaft projecting 60 through said hole, a dial having a hub portion, a sleeve between the shaft and the hub portion of said dial and projecting beyond said hub portion, a knob having a tubular 65 extension secured to the outer end of said sleeve, a second knob between the dial and the first knob and having an inner tubular extension rotatable around the tubular extension of the first knob and the hub portion of the dial, and means operatively connected between the second knob and the dial 70 to turn the latter; and through it the shaft, when the second knob is rotated.

4. In a device of the type described, a panel containing a hole, a shaft projecting 75 through said hole, a dial having a hub portion secured to said shaft, a knob having a tubular extension secured to the shaft beyond the hub portion of the dial, a second knob rotatable around the tubular extension 80 of the first knob and the hub portion of the dial, and means operatively connected between the second knob and the dial to turn the latter, and through it the shaft, when the second knob is rotated.

In testimony whereof I have hereunto set my hand this 24th day of January, 1925.

HENRY J. KASCH.
